To all whom it may concern:

Be it known that I, SAMUEL L. POMERANTZ, a citizen of the United States, and resident of Brooklyn, in the county of Kings and State of New York, have invented a new, original, and ornamental Design for an Advertising Powder-Puff-Display Stand, of which the following is a specification, reference being had to the accompanying drawing, forming a part thereof.

In the accompanying drawing:—

Fig. 1 is an elevational view of an advertising powder puff display stand, showing my new design, which consists of a stand with radial arms each supporting receptacles con-

taining powder puffs which are to remain intact as constituting an inseparable part of the entire article. The sides of the design not shown present the same appearance as the side shown in Fig. 1.

Fig. 2 is a plan view of Fig. 1.

I claim:—

The ornamental design for an advertising powder puff display stand, as shown and described.

Signed at New York in the county of New York and State of New York this 16th day of July A. D. 1930.
